[57] CLAIM

The ornamental design for an adjustable lounge seat, as shown and described.

DESCRIPTION

FIG. 1 is a perspective view of an adjustable lounge seat embodying the design of this invention.

FIG. 2 is a front elevational view of an adjustable lounge seat embodying the design of this invention.

FIG. 3 is a plan view of an adjustable lounge seat as shown in FIG. 2.

FIG. 4 is a bottom view of an adjustable lounge seat as shown in FIG. 2.

FIG. 5 is an end elevational view of an adjustable lounge seat as appearing from the rightward end in FIG. 2.

FIG. 6 is an end elevational view of an adjustable lounge seat as appearing from the leftward end in FIG. 2.

FIG. 7 is a view showing a use of an adjustable lounge seat.

FIG. 8 is a front elevational view of an adjustable lounge seat with legs thereof being folded.

FIG. 9 is a front elevational view of an adjustable lounge seat with legs thereof being folded and the back portion thereof being lifted.

FIG. 10 is a cross-sectional view taken along line 10—10 of FIG. 3.
